PROPELLION APPARATUS

John M. Holley, 3622 Lakeside Court, Tucker, Ga.
Filed Oct. 31, 1960, Ser. No. 66,064
2 Claims. (Cl. 115—28)

This invention relates to propulsion apparatus and, more particularly, to apparatus for trolling small boats.

It is an object of this invention to provide novel propulsion apparatus for small boats, and the like. Another object is to provide propulsion apparatus of the character described in which an advantageous adjustment feature is incorporated whereby the propulsion apparatus may be operated at maximum efficiency irrespective of the environment, i.e., the character of the craft, the character of the water surface, etc. Still another object is to provide novel propulsion apparatus for mounting on the transom of a small boat in which a novel fin is provided on a propeller shaft or tube. Other objects and advantages of this invention may be seen in the details of construction and operation set down in this specification.

The invention, in conjunction with an illustrative embodiment thereof, will be explained in the accompanying drawing, in which—

FIG. 1 is a fragmentary side elevational view of a small boat equipped with the inventive apparatus;

FIG. 2 is a top plan view of the apparatus-equipped boat of FIG. 1;

FIG. 3 is a fragmentary top plan view of the rearmost portion of the apparatus seen in FIG. 2; and

FIG. 4 is a fragmentary elevational view, partially in section, of an intermediate portion of the propulsion apparatus.

In the illustration given and with particular reference to FIG. 2, the numeral 10 designates generally a small boat, while the numeral 11 designates generally the propulsion apparatus embodying teachings of the invention. The propulsion apparatus 11 is equipped with a fin 12 at the extreme rear end thereof (also see FIG. 1), and the boat 10 is propelled by moving the apparatus 11 over a horizontal arc shown by the broken line arrows associated with the handle portion 13.

Now referring to FIG. 2, it will be seen that the propulsion apparatus 11 includes an elongated member 14 which conveniently can be constructed of lightweight tubing. Optimally, $\frac{3}{4}$ " diameter stock may be employed. Thus, a conventional rubber handle grip 13 may be readily installed at the forward end of the member 14. The member 14 is seen to include a horizontally-disposed portion 15 at one end thereof and a second horizontally-disposed portion 16 at the other end thereof. Intermediate the portions 15 and 16 is a vertically-inclined portion 17, giving the member 14 a generally Z-shape. The horizontal portion 15 is equipped with a pair of aligned openings 18 through which a bolt 19 extends in a generally vertical direction.

The bolt 19 is provided as part of a bracket generally designated 20 and which may be secured in the fashion shown to the transom 21 of the small boat 10. The bracket 20 also includes washers 22 mounted on the bolt 19 and the member 14 is confined on the bolt 19 by means of a wing-nut 23. It will be appreciated that the bolt 19 may be equipped with a shoulder or other abutment means for restricting the lower washer 22 against downward movement, thereby immobilizing the washer and confining the member 14 in the position shown. The openings 22 thus provide bearings for the member 14 so that the member 14 can be moved over a generally horizontal arc for the desirable pivotal movement developing movement of the small boat 10.

The portion 16 at the sternmost portion of the mem-

2

ber 14 is equipped with the fin 12, and for that purpose the fin 12 at its forward end is equipped with a longitudinally-extending, generally cylindrical integral portion 24 (see also FIG. 3). The portion 24 is equipped with generally horizontally-extending bores 25 aligned with openings 26 in the end portion 16 of the member 14. Bolts 27 extend through the aligned openings 25 and 26 to secure the fin 12 relative to the portion 16, the bolts 27 being retained in place by means of wing-nuts 28.

10 The fin 12 itself is desirably constructed of a flexible material such as rubber, and is seen to be bifurcated as at 29. The recess providing the bifurcation 29 is midway of the height of the fin 12 and thus divides the fin into an upper portion 30 and lower portion 31. Each 15 portion 30 and 31 is equipped with a pair of generally longitudinally-disposed, laterally extending ribs 32 and 33, respectively. A third pair of ribs 34 is provided between the upper pair of ribs 32 and the lower pair of ribs 33, the ribs 34 being aligned with the apex of the 20 recess providing the bifurcation 29.

As can be most readily appreciated from a consideration of FIG. 1, the fin 12 is outwardly flared, i.e., the upper and lower edges 35 and 36, respectively, diverge in proceeding away from the portion 24. By reference 25 to FIG. 3, it will be seen that the flat sides 37 and 38 of the fin 12 converge in proceeding away from the cylindrical received portion 24.

Means are provided in the intermediate portion 17 for varying the length of the member 14. This adjustment 30 means can be readily appreciated from a consideration of FIG. 4. The portion 17 is seen to include two tubular portions, the rearmost being designated in FIG. 4 by the numeral 39, and the more forward portion being designated by the numeral 40. As can be seen from FIG. 4, 35 the tubular element 40 is received within the tubular element 39. The forward end of the element 39 is seen to be equipped with male threads 41 and threadedly received over the element 39 is a sleeve or coupling element 42 which is equipped with female threads designated 43. 40 The extreme forward end 39a of the element 39 is seen to be equipped with a plurality of circumferentially-spaced, longitudinally-extending slits 44.

In operation, threading of the coupling 42 on the element 39 urges the tongue-like portions 45 necessarily developed by the slits 44 into gripping relation with the element 40. By unthreading the coupling 42, the gripping relationship is relieved and the element 39 can be moved relative to the element 40 to provide a different degree of telescoping.

50 Desirably, the element 40 is equipped with an annular flange 46 at the rearmost end thereof. The outer telescoping element 39 is equipped with cooperating flange means in the form of element 47, which together necessarily restrict the degree to which the element 40 can be 55 withdrawn from the element 39. Desirably, a second coupling arrangement may be provided in the horizontal portion 15 as at 48 (see FIG. 1).

In the operation of the device, the handle 13 is grasped 60 by the operator as one would grasp a tiller, and moved in a reciprocal fashion over a horizontal arc about the pivot provided by the bolt 19. By loosening the locking bolt 20a provided as part of bracket 20, the entire device 11 may be removed from a small boat for installation on another boat or storage. When the same is installed on a 65 boat having a higher or lower transom, advantageously the length and the degree of penetration of the apparatus 11 may be altered. This is conveniently achieved by unthreading the coupling 42 to permit the tongue-like portions 45 to release their grip on the element 40. Thereafter, the element 39 may be repositioned to give a greater or shorter length to the element 14 and, at the same time,

a different degree of water penetration. In some instances, a change of water penetration may be advisable because of the character of the water surface, i.e., extreme waves, or the like. The change in length of the device also makes for different leverages when the same are desired.

The construction and contour of the fin 12 also work for efficient operation in that the bifurcated stern end of the fin develops a lashing action at the end of each horizontal arc.

While, in the foregoing specification, I have set forth a detailed description of an embodiment of the invention for the purpose of illustrating the same, many variations in the details herein given will be appreciated by those skilled in the art without departing from the spirit and scope of the invention.

I claim:

1. In propulsion apparatus for mounting on a small boat transom, an elongated, generally Z-shaped member defined by generally horizontally extending integral legs at the ends thereof and an intermediate, vertically inclined portion coupling said legs, pivot means on one of said legs for moving said member through a generally horizontal arc when said pivot means is secured to said transom, a generally vertically disposed, flat resilient bifurcated fin secured to the other of said legs and extending away therefrom, said fin means tapering in thickness in proceeding away from said inclined portion and tapering in width in proceeding toward said inclined portion, said inclined portion comprising a hollow tubular element and a second element telescopically received therein, the

end of said tubular element receiving said second element being equipped with longitudinally-disposed, circumferentially spaced slits, and sleeve means releasably mounted on said tubular element urging the slit-equipped end of said tubular element into gripping engagement with said second element.

2. In propulsion apparatus for small boats, and the like, an elongated member equipped with a handle at one end and fin mounting means at the other end, a bracket on said member adjacent to but spaced from said one end for attaching said member to said boat for pivotal movement in a generally horizontal plane, a fin on said fin-mounting means, said fin being disposed in a generally vertical plane and constructed of flexible material, said fin having its thickness dimension disposed generally horizontally, said thickness dimension decreasing horizontally away from said fin mounting means, and means between said bracket and fin for varying the portion of said member between said bracket and fin, said portion being angularly upwardly inclined when said handle means and said fin have their long dimension disposed generally horizontally.
